UNITED STATES PATENT OFFICE.

WALTER KIESER, OF CHARLOTTENBURG, GERMANY, ASSIGNOR TO GENERAL ELECTRIC COMPANY, A CORPORATION OF NEW YORK.

REGULATING SYSTEM FOR STEAM-TURBINES.

1,121,019.

Specification of Letters Patent. Patented Dec. 15, 1914.

Application filed September 23, 1914. Serial No. 863,070.

To all whom it may concern:

Be it known that I, WALTER KIESER, a citizen of the Swiss Republic, residing at Charlottenburg, Germany, have invented certain new and useful Improvements in Regulating Systems for Steam-Turbines, of which the following is a specification.

This invention relates to that class of steam turbines whose exhaust steam is utilized in heating, cooking or other industrial processes, and its object is to so arrange the system that both the turbine and the consumption devices will operate satisfactorily at all times, irrespective of each other and of changes taking place in one or the other. With this end in view, the valve admitting high pressure steam to the turbine is controlled by a governor responsive to changes in the speed of the turbine, and this governor also controls two other valves, one of which admits high pressure steam to the exhaust pipe of the turbine to supplement any lack of exhaust steam, while the other valve permits an escape of any excess of exhaust steam not taken by the consumption devices. Furthermore, these two valves are also under the control of a device responsive to variations in the pressure of the exhaust steam.

The accompanying drawing is a diagrammatic illustration of a regulating system embodying my improvements.

The turbine 1 receives high pressure steam from the main 2, the admission being regulated by a valve means such as 3 actuated by a speed governor 4 driven from the turbine shaft. The governor operates the valve 3 preferably through a motor 5 to which fluid pressure is admitted by a pilot valve 6, pivotally connected to the floating lever 7, which is pivoted at one end to the stem 8 of the valve 3 and at the other end to the rod 9 which receives vertical movement from the collar 4^a of the governor.

The exhaust pipe 10 of the turbine is suitably connected to consumption devices for heating, cooking or other purposes. At some convenient point, a pipe 11 branching from the high pressure main 2, connects with the exhaust pipe. The pipe 11 is controlled by a valve 12 whose stem 13 is connected to an intermediate point of a floating lever 14. One end of this lever is pivoted to the stem 15 of another valve 16 which controls an exit from the exhaust

pipe. This exit may open to the atmosphere, or to a conduit leading to the condenser. The opposite end of the lever 14 is pivoted to the rod 17 of a hydraulic or other motor 18, having a pilot valve 19 attached to a lever 20. One end of this lever is pivoted to the rod 17 and the other is connected with a lever 21 pivoted to the moving collar 4^a of the speed governor.

A pressure responsive device has its movable abutment 22 connected by a rod 23 to the lever 21, and is exposed, through the pipe 24, to the pressure of the exhaust steam in the pipe 10. A spring 25 opposes this pressure on the under side of the abutment 22.

The operation is as follows: Assuming the consumption of exhaust steam to remain constant, if now the load on the engine decreases, the governor will speed up and lift one end of the lever 21, which will fulcrum on the rod 23 and cause the motor 5 to partially close the valve 3. At the same time, by the downward movement of the other end of the lever 21, the motor 18 is caused to lift the lever 14, which fulcrums on the stem 15 and opens the valve 12. This admits high pressure steam to the exhaust pipe 10, so that the pressure therein is maintained constant, notwithstanding the reduction in the amount coming from the turbine. On the other hand, should the load on the turbine increase, the valve 3 will be opened wider, the valve 12 will remain closed, and the blow-off valve 16 will be opened to relieve the consumption devices of the excess of steam exhausting through the pipe 10. It thus appears that variations in the load on the turbine will not affect the constant supply of steam to the consumption devices. Now assume a change in the demand of the consumption devices, say a greater demand, with no change in the load on the turbine. This causes a drop in the pressure in the exhaust pipe which permits the spring 25 of the pressure-responsive device to push down the lever 21, fulcruming on the collar 4^a. The motor 18 thereupon lifts the valve 12 and admits high pressure steam to the exhaust pipe to make up the deficiency. This action occurs without disturbing the valve 3 which controls the turbine. If on the other hand, some of the consumption devices are shut down, while the load on the turbine re-

110

2 mains constant, the pressure in the exhaust pipe will rise. The movable abutment of the pressure responsive device will rise, lifting the lever 21 and causing the motor 18 to open the blow-off valve 16 to relieve the excess of exhaust pressure; and this without disturbing the valve 3. The system is thus perfectly flexible, and compensates readily for any change either in the load on the turbine or the demand of the consumption circuit, without, in either case, disturbing the other element in the combination.

5 In accordance with the provisions of the patent statutes, I have described the principle of operation of my invention, together with the apparatus which I now consider to represent the best embodiment thereof; but I desire to have it understood 20 that the apparatus shown is only illustrative, and that the invention can be carried out by other means.

What I claim as new and desire to secure by Letters Patent of the United States, is:—

25 1. The combination with a steam turbine supplying exhaust steam to consumption devices, of a speed governor, a valve for admitting high pressure steam to the turbine, a valve admitting high pressure steam to the 30 exhaust pipe, and a valve for blowing off steam from said pipe, all three valves being controlled by the speed governor.

35 2. The combination with a steam turbine, supplying exhaust steam to consumption devices, of a speed governor, a valve for admitting high pressure steam to the turbine, a valve admitting high pressure steam to the exhaust pipe, and a valve for blowing off steam from said pipe, all three valves being 40 controlled by the speed governor, a device responsive to pressure changes in the exhaust

pipe, and operative connections between said device and said last two named valves.

3. The combination with a steam turbine 45 supplying exhaust steam to consumption devices, of a valve admitting high pressure steam to the exhaust pipe, a blow-off valve on said pipe, a floating lever pivoted to the stems of said valves, and means for operating said lever in response to changes in load 50 on the turbine and demand of the consumption devices.

4. The combination with a steam turbine 55 supplying exhaust steam to consumption devices, of a valve admitting high pressure steam to the exhaust pipe, a blow off valve on said pipe, and operative connections for opening the first valve when the load on the turbine decreases, or the demand of the consumption devices increases, and for opening 60 the blow-off valve under opposite conditions.

5. The combination with a steam turbine 65 supplying exhaust steam to consumption devices, of a valve admitting high pressure steam to the exhaust pipe, a blow-off valve 70 on said pipe, a speed governor for the turbine, a pressure responsive device connected with the exhaust pipe, and operative connections between said valves and the governor and pressure regulator whereby an increase of load on the turbine or a decrease in the demand of the consumption devices will cause an opening of the blow-off valve, and opposite conditions an opening of the high pressure steam valve. 75

In witness whereof, I have hereunto set my hand this second day of September, 1914.

WALTER KIESER.
